UNITED STATES PATENT OFFICE.

ANSEL S. WYSONG, OF LOS ANGELES, CALIFORNIA, ASSIGNOR TO INTERNATIONAL GAS, POWER AND APPLIANCE COMPANY, A CORPORATION OF ARIZONA.

PROCESS IN PRODUCING FUEL FOR INTERNAL-COMBUSTION ENGINES.

Application filed March 12, 1924. Serial No. 698,594.

To all whom it may concern:

Be it known that I, ANSEL S. WYSONG, a citizen of the United States, residing at the city of Los Angeles, county of Los Angeles, State of California, have invented or discovered a new and useful Process in Producing Fuel for Internal-Combustion Engines, of which the following is a specification.

10 Heretofore in internal combustion engines it has been necessary to use liquid hydrocarbon fuel of a light gravity in order that it could be fired in the cylinders of the engines, and to that end the common practice 15 has been to use gasoline of a fairly high grade. I have discovered that I can use a grade of hydro-carbon liquid of a lower grade than the lowest grade of gasoline and can also use any grade of gasoline by combining or mixing with such fuel and air a due proportion of acetylene gas as the fuel is drawn into the engine cylinders. I have discovered that the introduction of acetylene 20 gas with the hydrocarbon fuel and air enables the mass to be fired or exploded. I have discovered that if the mixture of air, fuel and acetylene gas is thoroughly broken up and atomized and commingled before it enters the cylinders it produces better 25 results than if not thoroughly atomized. I have also discovered that better results are obtained by commingling and atomizing with the hydrocarbon fuel, air and water and acetylene gas.

30 In the drawings forming a part of this application, I have illustrated an apparatus in which the hydrocarbon fuel and water and air and the acetylene gas are atomized and commingled before being admitted into 35 the cylinders.

Referring to the drawings:

Fig. 1 is a side elevation of a stationary explosion engine equipped for utilizing my discovery or invention;

40 Fig. 2 is a central vertical section of the carburetor used in practicing my invention;

Fig. 3 is a bottom plan of the carburetor;

Fig. 4 is a sectional detail of the acetylene 45 gas check valve to control the back fire should any occur;

In the different views, different scales of illustration are used.

Referring to Fig. 1, the usual parts of a stationary explosion engine comprising 50 cylinders, pistons and intake and exhaust

manifolds and connected and operative parts are used. The carburetor 10 is illustrated in Fig. 2 and comprises a casing 11 in one side of which is liquid fuel chamber 12 which is connected by pipe 13 with tank 14 in which is carried the hydrocarbon fuel liquid. A valve 15 operated by lever 16 regulates the admission of liquid into chamber 12. Lever 16 is controlled by the celluloid ball float 17 to cut off the flow of liquid into chamber 12 when it rises to a predetermined height.

A port 18 connects with channel 19 which opens through port 20 into the wheel chamber 21. A regulating valve 22 controls the flow of liquid through port 20. In the other side of casing 11 is a water chamber 23 which is connected by pipe 24 with tank 25 in which is carried the water supply. A valve 26 operated by lever 27 regulates the admission of water into chamber 23. Lever 27 is controlled by the celluloid ball float 28 to cut off the flow of water into chamber 23 when it rises to a predetermined height.

A port 29 connects with chamber 30 which opens through port 31 into wheel chamber 21. A valve 32 controls the flow of water through port 31. Channels 19 and 30 are in web 33 on the bottom of casing 11. Air ports 34 open through the bottom of casing 11 into chamber 21. A shaft 35 projects through the bottom of casing 11 and has a nut 36 and a lock nut 37. Shaft 35 may have a chamber 38 in the side thereof for the reception of screw 39 to prevent shaft 35 from rotating.

On shaft 35 and within chamber 21 is valve 40 which when the engine is not operating closes ports 20 and 31. Revolvably mounted on shaft 35 are the atomizing wheels 41 and 42 which are provided on the periphery thereof with helical vanes 43 and 44 which are reversely pitched as to each other. The top of wheel 42 is dished and has ports 45 therein to lead any liquid which may pass the wheels unatomized onto wheel 41.

Rigidly mounted on shaft 35 is a hub 46 from which extends upwardly and slightly angularly blades 47. These blades extend into the intake manifold 48 and their angularity is the reverse of the pitch of the vanes of wheel 42. Manifold 48 has a throttle valve 49 which is operated in the usual manner. Between valve 49 and the engine cylinders is a valve chamber 50 in which is mounted valve 51.

100

105

110

Valve 51 operates as a check to prevent back fire from reaching the carbureter and to direct the fuel from the carbureter across ports 52. A collar 53 screws upon shaft 54 on which shaft valve 51 is carried and tensions spring 55 to hold valve 51 as firmly on its seat as is desired.

The suction of the pistons draws air through ports 34, air ducts 34' and at the same time causes valve 40 to rise off its seat, thereby admitting oil and water from chambers 12 and 23. The air, oil and water are drawn up through the vanes of wheel 41 thereby causing it to revolve rapidly to the left. After passing wheel 41 the air, oil and water encounter the vanes of wheel 42 thereby causing it to revolve rapidly to the right. After passing wheel 42 the air, oil and water encounter blades 47 and they cause it to revolve rapidly to the left. In the passage of the oil, water and air through wheels 41 and 42 and blades 47 the oil and water are thoroughly atomized and commingled and pass on into chamber 50 and commingle with the acetylene gas which is admitted into chamber 50 through pipe 56 from the prestolite tank 57. In the place of tank 57 I may provide an acetylene gas generator of usual construction.

Instead of admitting the acetylene gas into the manifold above the wheel chambers, I may introduce the same through a pipe 58 between ports 20 and 31. By the admixture of acetylene gas, I am enabled to use a much heavier grade of liquid hydrocarbon fuel in an explosion engine than is possible without the use of acetylene gas. The commingled oil, water and air and gas are compressed and fired in the usual manner. If it is not desired to use water, I may dispense with the water chamber 23 and connected tank and valves. While I have found that by the use of water I get more mileage and less fouling of the spark plugs and cylinders

in an automobile, it will be understood that I can get fairly good results from the use of liquid hydrocarbon fuel and air and acetylene gas and that I can use any standard make of carbureter when I dispense with the use of water.

Having described my invention or discovery, I claim:

1. The process of using heavy liquid hydrocarbon oil and water in explosion engines which consists of atomizing and commingling the heavy hydrocarbon liquid and water with acetylene gas and air and then admitting them into the cylinders and compressing and firing the same.

2. The process of using heavy liquid hydrocarbon oil and water in an explosion engine which consists of atomizing and commingling the heavy liquid oil and water and air and then admitting acetylene gas into the atomized and commingled oil and water and air and then admitting them into the cylinders and compressing and firing the same.

3. The process of using liquid hydrocarbon in an explosion engine which consists of violently agitating and atomizing and commingling the liquid hydrocarbon and air and admitting into the commingled liquid and air acetylene gas and then admitting the same into the engine cylinder and then compressing and firing the same.

4. The process of using liquid hydrocarbon in an explosion engine which consists of violently agitating and atomizing and commingling the liquid hydrocarbon with air and also mixing with this fuel acetylene gas and admitting the same into the cylinder and then compressing and firing the same.

In witness that I claim the foregoing I have hereunto subscribed my name this 28th day of February, 1924.

ANSEL S. WYSONG.
